BOTTLE TRAY

William Geisler, Tenafly, N. J., assignor to Wilbro Corporation, New York, N. Y., a corporation of New York

Application August 17, 1949, Serial No. 110,708

2 Claims. (Cl. 229—32)

1

This invention is directed to a modification of the shipping case disclosed in my co-pending application Ser. No. 82,749, filed March 22, 1949.

The object of the present invention is to provide a "tray" for holding bottles, as distinguished from a "case" such as shown in my above-mentioned application, which is the term usually employed for containers which are the full height of the bottles. Shallow trays made of wood are used to almost the same extent as the so-called cases of full bottle height, and the object of my invention is to provide a tray, as distinguished from a case, which is formed of fibreboard with reinforcing members generally similar to the case described in my above-mentioned application and which possesses certain advantages over the wood trays now largely employed.

The object of the invention is to provide a tray of the character described, wherein the entire tray, including the strips forming the divisions between the bottles, may be shipped knocked down in one piece for erection at the bottling plant, as required for use, thereby effecting a large saving in freight and storage expense over the conventional wooden tray.

A further object of the invention is to provide a tray of the character described so constructed that when the trays full of bottles are stacked, the bottles and trays interlock in such manner that a large number of trays may be handled on a pallet as a single load without danger of the upper trays of the outside tiers falling off the stack, as now frequently occurs when wooden trays containing bottles are so handled.

A further object of the invention is to provide a tray of the character described which is of lower first cost than the conventional wooden tray, which lasts longer and also requires less maintenance cost than the standard tray.

Referring to the drawings:

Fig. 1 is a perspective view showing one side of the blank with the attached reinforcing members;

Fig. 2 is a perspective view of the other side of the flat blank with the strips forming the bottle separators collapsed and ready for shipment;

Fig. 3 is a perspective view of the improved tray when erected and ready for use;

Fig. 4 is a sectional view showing two trays of bottles stacked one on the other;

Fig. 5 is a detail view on line 5—5 of Fig. 2; and

Figs. 6 and 7 are perspective views of a modified form of tray in erected and collapsed form respectively.

2

Referring to the drawings, particularly to Fig. 1, 1 indicates the middle portion of the blank which forms the bottom of the erected tray. The bottom portion is provided at each end with end flaps 2 which form the end walls of the tray and with side flaps 3 which form the side walls of the tray. At each end of each side flap 3 is a tab or supplemental flap 4 which when the tray is erected folds against the inner side of the end flap 2. In the preferred form illustrated in the drawings the tabs 4 are of a length equal to the width of the flaps 3, but if it is desired that when the tray is erected the end walls of the tray will be of double thickness throughout, the tabs 4 may be longer than the width of the side flaps.

Attached to the outside face of the blank along the line corresponding with the score lines between the end flaps 2 and the bottom portion 1 of the blank, and extending over the score lines between the said flaps 3 and the tabs 4 is a reinforcing angle 5 such as described in my above-mentioned application and consisting preferably of molded rubber. Other materials such as fiber impregnated plastic and the like, may be used instead. The angles 5 are attached to the edge of the bottom portion 1 and to the ends of the flaps 3 adjacent the score lines between the flaps 3 and the tabs 4. The other side of the angle is not attached to the end flaps 2 and the tabs 4 until the tray is erected. The side of the angle which is subsequently attached to the flaps 2 and tabs 4 is notched at its edge corresponding with the bottom corners of the tray and the attached side of the angle is preferably scored or weakened as indicated at 6, so that the angle will bend along these weakened lines when the case is erected. In addition to the angle 5 I preferably attached to the outer face of the bottom portion 1 of the blank, along its longitudinal edges, flat reinforcing strips 7 of the same thickness as the attached sides of the angle 5 so that the entire perimeter of the bottom of the tray is reinforced with the rubber strips.

The end flaps 2 are cut through along the line indicated at 8 to provide hand holes in the ends of the trays. When the tray is erected the tongues 9 are folded up inside the tray in the manner shown in Fig. 3. If necessary, the tabs 4 are cut away to provide openings registering with the openings in the end flaps 2 when the tray is erected.

Attached to the outer marginal edges of the flaps 2 and 3 are additional reinforcing angles 11 which serve to stiffen and protect the upper edges of the side walls of the trays. These angles

are preferably smaller than the reinforcing angles 5.

When the tray is flattened for shipment the end flaps 2 and projecting tabs 4 of the flap 3 are folded against the adjacent portions of the part 1 and the flaps 3, respectively, so that the thickness of the collapsed tray is no greater than the width of the angle 5.

The partition assembly for the bottles is also formed and attached to the knocked down tray. As shown in Fig. 3 the partitions consist of three longitudinal strips and five transverse strips, thereby providing spaces for 24 bottles. The two outer longitudinal strips 12 are composed of a single strip of fibreboard which is folded to a rectangular configuration as shown in Fig. 3. The meeting ends of the strips are stapled or otherwise attached to the adjacent face of one of the end flaps 2 and the strip is scored at points corresponding to the four corners of the rectangle. The strip is slotted on its upper edge at spaced intervals for interlocking with the transverse strips 15 which are similarly notched in the usual manner to interlock with the longitudinal strips. The middle longitudinal strip 16 is separate from the two side strips 12 and is assembled with the transverse strips by the interlocking notches, but is not otherwise attached to the blank. The entire partition assembly is thus attached to one edge flap of the knocked down blank and may be collapsed against the inner face of the flap, as shown in Fig. 2, and the flap may be folded down against the adjacent face of the bottom portion 1 of the blank to an extent such that the thickness of the folded down flap and partition assembly is no greater than the width of the rubber angle.

When the tray is erected the end flaps 2 are turned to vertical position, that is, at right angles to the bottom section 1, and the assembled partitions pulled out until the strip 12 assumes its original rectangular shape. The tabs 4 are then turned to right angles to the flaps 3 and the flaps 3 are then brought to vertical position with the tabs 4 extending on the inside of the end flaps 2. As the flaps 3 are turned to vertical position the ends of the reinforcing angles 5 beyond the cut-out portions 6 will also be turned to vertical position, bringing the unattached sides of the end portions of the angles into position overlying the ends of the flaps 2.

The tongues 9 are then bent inwardly through the slots 8 in the flaps 4 and folded up against the inside of the flaps. The various overlapping members of the erected tray are then stapled together to provide a permanently erected tray. An ordinary portable stapling head may be used for this purpose. The additional staples are preferably driven into the sides of the angles 5 which overlie the end flaps 2 along the bottom and also along the end portions of the angles which in the erected tray form reinforcing members embracing the vertical corners. The end portion of the rectangular strip 12 of the partition assembly is also stapled to the end wall 2 of the erected tray, and the tongues 9 are stapled to the angle 5 and the overlapping portions of the flaps 2, thereby completing the tray.

The sides of the angles 5 which are attached to the bottom part 1 of the tray and the strips 7 are preferably of a width such that the bottles forming the outside end and side rows of the underlying tray will fit just within the edges of the reinforcing angles and strips, as indicated in Fig. 4, thereby interlocking the trays when the

trays full of bottles are stacked. When so interlocked the trays may be stacked to a much greater height on a truck or pallet than is possible with the wooden trays now in use, without danger of the upper trays falling off, even when transported in an open truck or lifted on a pallet.

In Figs. 6 and 7 I have shown a modified arrangement of the partition structure whereby the collapsed tray will occupy less space than when constructed as above described. To this end the partitions are made in two separate sections. One section consists of two transverse partitions 21 at one end of the tray and three longitudinal partitions which extend not quite midway of the length of the tray. The other section consists of the two transverse partitions 22 at the other end of the tray, the middle transverse portion 23 and three longitudinal partition sections which extend slightly more than half the length 20 of the tray. When the partition assembly is erected the longitudinal partitions at one end of the tray are aligned with the partitions at the other end of the tray, as shown in Fig. 6.

The transverse partitions 21 at one end of the tray are in the form of a continuous rectangle with the end 24 attached, as shown, to one side wall of the tray. In like manner the transverse partitions 22 at the other end of the tray are in the form of a continuous rectangle and the adjacent end 25 of the continuous strip which forms the rectangle is attached to the opposite side wall of the tray.

In Fig. 7 I have shown the tray with the partition assembly above described as it appears when collapsed for shipment. As here shown the section of the partition assembly comprising the transverse partitions 21 is collapsed against the face of the side wall of the tray to which the ends of the partitions 21 are attached, while the partition section comprising the strips 22 is collapsed against the opposite side wall of the tray. The tabs 4 at the end of the side wall where the partition strips are attached overlie the point of attachment of the nearest partition strip, while at the other end of the side wall the tab is folded flat against the face of the flap with the collapsed partitions overlying the tabs. The collapsed partition structure, when divided in two as described, is no thicker than the width of the reinforcing angles and consequently the collapsed trays may be stacked one on the other with the flat side of the reinforcing angles of one tray resting on the top edges of the collapsed tray beneath.

The rubber reinforcing strips while stiff enough and rigid enough to hold the tray in shape, even under rough handling, have some cushioning effect which protects the bottles against breakage to a much greater extent than the wooden tray when the trays are bumped against each other or dropped. Also, the rubber reinforcing members serve to protect the trays, particularly when the trays are empty or loaded with empty bottles, from damage due to rough handling.

The partition structure, when once set up and erected, becomes a permanent part of the tray, and while it may be readily replaced in case of damage by withdrawing the staples by which it is attached to the side walls of the tray, the partition structure may ordinarily be repaired by stapling over the broken section a short strip of fiberboard cut and scored to fit the corner alongside the area of damage.

The collapsed partition structure may be sold unattached to the tray and inserted in the tray 75 after the tray is erected. If desired the partition

structure may be made with both transverse and longitudinal sections bent to rectangular configuration and stapled to the walls of the tray to thereby furnish intermediate supports for both the side walls and end walls of the tray.

While my present invention is described as applied to a tray as distinguished from a case, it will be apparent that the various features of the invention may be used with equal advantage in a case wherein the side walls are the full height of the bottle and in the appended claims the word "tray" is not intended to exclude cases or other containers having the features recited in the claims.

While I have shown and described the preferred form of my improved tray, it will be understood that the invention is not limited to the details of construction herein shown and described, except insofar as recited in the appended claims.

I claim:

1. A collapsed reinforced carrier for bottles and the like comprising a sheet of paper board cut and scored to provide side and end flaps, reinforcing angles of semi-rigid plastic material attached to the sheet of paper board along certain of said score lines adjacent the portion thereof forming the body of the carrier with the corner of said angle alined with said score line and with the unattached portion of said angle projecting upward-

ly beyond the upper face of said bottom portion of said carrier and a collapsed partition assembly attached to the inner face of one of the flaps of said collapsed carrier said connection providing a fold line coincident with the end of one of said partition strips and the face of said flap so that when the flap to which the collapsed partition assembly is attached is folded against the face of the bottom portion of said collapsed carrier the partition assembly will lie flat against said bottom portion.

2. A collapsed reinforced carrier as recited in claim 1, wherein the thickness of the collapsed partition assembly and the flap to which it is attached is less than the height of the upstanding portion of the reinforcing angle.

WILLIAM GEISLER.
